Patented Nov. 8, 1966

206,171

TOKEN-OPERATED AMUSEMENT GAME MACHINE

Frederick N. Kayden, Sterling Road, Harrison, N.Y., and
Jerry E. Poncher, 303 N. Deere Park, Highland Park,
Ill.

Filed June 16, 1965, Ser. No. 85,769

Term of patent 3½ years

(Cl. D34—5)

FIGURE 1 is a front elevation view of the token-operated amusement game machine showing our new design;

FIGURE 2 is a side elevation view thereof;

FIGURE 3 is a rear elevation view thereof; and

FIGURE 4 is a top view thereof.

The dominant features of our design reside in the portions shown in full outlines.

We claim:

The ornamental design for a token-operated amusement game machine, substantially as shown and described.
